UNITED STATES PATENT OFFICE

MATSON C. TERRY, OF MANSFIELD, OHIO, ASSIGNOR TO WESTINGHOUSE ELECTRIC & MANUFACTURING COMPANY, A CORPORATION OF PENNSYLVANIA

DESIGN FOR A REFRIGERATOR COOLING UNIT

Application filed March 20, 1930. Serial No. 34,980. Term of patent 14 years.

To all whom it may concern:

Be it known that I, MATSON C. TERRY, a citizen of the United States, residing at Mansfield, in the county of Richland and State of Ohio, have invented a new, original, and ornamental Design for Refrigerator Cooling Unit, of which the following is a specification, reference being had to the accompanying drawing, constituting a part hereof.

Figure 1 is a perspective view and

Fig. 2 is a front elevational view of a refrigerator cooling unit showing my new design.

I claim:

The ornamental design for a refrigerator cooling unit substantially as shown.

In testimony whereof, I have hereunto subscribed my name this 7th day of March, 1930.

MATSON C. TERRY.
